UNITED STATES PATENT OFFICE.

LESLIE BROWN, OF SAG HARBOR, NEW YORK, ASSIGNOR TO JOSEPH FAHYS & COMPANY,
OF NEW YORK, N. Y.

DESIGN FOR A HAND-MIRROR.

49,987.

Specification for Design.

Patented Dec. 5, 1916.

Application filed July 23, 1915. Serial No. 41,611. Term of patent 7 years.

To all whom it may concern:

Be it known that I, LESLIE BROWN, a citizen of the United States, residing at Sag Harbor, in the county of Suffolk and State of New York, have invented a new, original, and ornamental Design for Hand-Mirrors, of which the following is a specification, reference being had to the accompanying drawing, forming part thereof, and in which—

Figures 1 and 2 are front and back elevations; and Fig. 3 is a cross section of a hand mirror embodying my new design.

I claim:

The ornamental design for a hand mirror, as shown.

LESLIE BROWN.
